[57] **CLAIM**

The ornamental design for a bandage backing, as shown and
described.

DESCRIPTION

FIG. 1 is a perspective view of a bandage backing showing
our new design;

FIG. 2 is a top plan view thereof;

FIG. 3 is a bottom plan view thereof; and,

FIG. 4 is a side elevational view thereof, all side elevational
views being identical thereto.

The broken lines in the drawing are for illustrative purposes
only and do not form part of the claimed design.
